UNITED STATES PATENT OFFICE

172,054

ELECTRICAL POWER UNIT CASE FOR PHOTOFIN APPARATUS

Robert L. Pennock, Jr., Denver, Colo., assignor to
Heiland Research Corporation, Denver, Colo., a
corporation of Colorado

Application April 10, 1953, Serial No. 24,443

Term of patent 14 years

(Cl. D26—6)

To all whom it may concern:

Be it known that I, Robert L. Pennock, Jr., a citizen of the United States, residing at Denver, in the county of Denver, State of Colorado, have invented a new, original, and ornamental Design for an Electrical Power Unit Case for Photoflash Apparatus, of which the following is a specification, reference being had to the accompanying drawings forming part thereof and wherein:

Figure 1 is a front elevational view of the electrical power unit case for photoflash apparatus showing my new design;

Figure 2 is a top plan view thereof;

Figure 3 is a rear elevational view thereof; and
Figure 4 is a side elevational view thereof.

I claim:

The ornamental design for an electrical power unit case for photoflash apparatus, as shown.
